MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC-APPLIANCE RECEIVING BOX.

1,411,086.

Specification of Letters Patent. Patented Mar. 28, 1922.

Application filed April 6, 1921. Serial No. 458,908.

To all whom it may concern:

Be it known that MONROE GUETT, a citizen of the United States, residing at Hartford, in the county of Hartford and State 5 of Connecticut, has invented certain new and useful Improvements in Electric-Appliance Receiving Boxes, of which the following is a specification.

This invention relates to an electric-appliance receiving box. As will be understood the box may contain any one or more in fact, of electric appliances. As an illustration of one form of article which can be advantageously housed in the box, is an electric switch and its adjuncts such as the fuses if present, the terminals and certain of the connections. I have a number of objects in view among them being the provision of an article of the character set forth which will 10 effectually sustain and permit the proper action of a switch yet which will effectually prevent access to the box when the switch is in the closed relation yet will permit such access when the switch is in the open condition, means also being desirably provided to permit an attendant to reach the interior of the box when it is necessary initially to connect the parts therein electrically with an 15 exterior source of supply.

The invention is rather broad in character but in the drawings accompanying and forming part of the present specification, I have shown in detail one of the several forms of embodiment of the invention which will 20 be described in detail in the following description. Obviously I am restricted in no sense to this particular disclosure. I may depart therefrom in a number of respects within the scope of the invention defined by 25 the claims following said description.

Referring to said drawings:

Figure 1 is a longitudinal section of a box involving the invention and showing the cover by full lines as closed and certain other 30 relations of the cover by dot and dash lines.

Fig. 2 is a somewhat similar view but with the switch actuator in a position reverse to that shown in Fig. 1.

Fig. 3 is a practically similar view with 35 the switch actuator in the position shown in Fig. 1 and the dotted lines showing certain shifted relations.

Fig. 4 is a top plan view of the rear lower half of the box or the left portion thereof.

Fig. 5 is a cross section on the line 5—5 of Fig. 2.

Like characters refer to like parts throughout the several views.

The box shown may be made of any suitable shape or material. Generally it is of 40 oblong rectangular formation and is formed from sheet metal. The one shown comprises a body as 2 and although it is shown as having a bottom 3, this is not always necessary. As I have already observed the box may 45 enclose electrical appliances of various characters but it is best adapted to receive a switch and in this case the switch mechanism is generally mounted on a block or base as 4 of some suitable insulating material. In 50 the event that the body 3 be not present in any particular installation, the block or base 4 or equivalent means would merely be enclosed by the walled portion of the box which in the construction shown is the body thereof. As shown the base or block 4 sustains 55 upon its upper side contacts as 5 co-operative with a switching member as 6 which is assumed to be "off" in Fig. 1 which is the only view in fact in which it appears. As 60 associated with the contacts 5 are wires or conductors as 7 and with them are in electrical connection one or more fuses as 8.

The cover, lid or closure for the box is 65 denoted by 9 and as shown like the body or box, is of sheet metal having along its opposite sides and upper end flanges as 9' to fit the sides and the upper end of the body of the box when the cover is closed. The cover 70 is generally made of the same material of 75 which the body and bottom of the box, is composed.

As represented the cover 9 comprises a lower section as 10 and an upper section as 11 which may be related to each other in 80 various ways generally flexibly, and hinges as 13 are shown for connecting the two cover sections. As shown the upper section 11 is slightly longer than the other, and superficially they are collectively of oblong 85 rectangular shape to conform to the character of the box body 2.

In practice a suitable catch or latch is provided to hold the cover 9 against acci-

dental movement and for this purpose the spring catch 14 is shown, the butt thereof being riveted or otherwise suitably united to the upper front wall of the box body, the 5 working portion of the latch extending through a slot 15 in the top 9 and having a shoulder 16 to engage over the top of the box above or forward of the slot. By pulling back the upper or free portion of the latch 10 the shoulder or effective portion 16 will be freed from the lid or cover so that the latter may be swung open if conditions permit this.

I have alluded to a switching member as 15 6 which is one of a kind suitable for my purposes and which may be housed in the box. To cause the movement of this switching member between "on" and "off" positions a suitable actuator such as 17 is provided. As shown the actuator comprises a body as 18 of suitable shape and which may be of practically segmental form, a handle or grasping portion 19 extending upward from the body. In practice the actuator is 20 supported generally by the bracket or bearing which carries the switching mechanism and which is sustained by the block or base 4. Although the actuator may have any kind of desired movement it is assumed to 25 be pivotally mounted so that it can oscillate or swing. It is shown in its two extreme positions in Figs. 1 and 2 respectively. It is operatively connected with the switching mechanism or more properly with the 30 switching member 6 in some convenient way as by links 20. At about the time the dead center position of the actuator is reached, the switching member 6 is snapped to one of its two final positions by spring means as 35 40 quite common. As shown the cover 9 has a longitudinal slot 21 and through the same the actuator extends in such position that the handle or grasping portion 19 is externally accessible for operating the switch. 45 The major portion of the slot 21 is formed in the cover section 10. As shown the cover 9 has on the section 10 thereof at opposite sides of the slot 21, the flanges or extensions 22 which may consist of practically L-shaped 50 pieces the bases of which are suitably attached to said section 10 at opposite sides of the slot. These cams or flanges 22 co-operate as shown with stud means such as the pin 23 which is driven through the actuator 55 17 at about the base or butt of the handle 19 thereof and the opposite terminals of which are flattened, the flattened faces being co-operative with the two cams 22 to lock or hold down part 10 of the cover 9. As 60 shown the cover has associated therewith wings as 24 and which may consist of segmental plates fastened in some convenient way to the under or inner side of the section 11 of the cover. As illustrated the 65 wings or plates 24 have in them segmental

slots 25 to receive studs 26 respectively extending from the inner opposite sides of the body 2 of the box, each slot having at one end a lateral offset or branch 27.

In Fig. 2 the cover 9 is assumed to be 70 locked in its closed relation, the terminal portions of the stud or pin 23 overlying the two cams 22 on the cover and the studs 26 being in the offsets 27. In view of this condition it is clear that the cover 9 is positively and effectually locked in place on the body 2 the studs 23 obviously blocking with positiveness the lifting of the cover and thus preventing the stud 26 passing around the slot 25. To free the cover the actuator 80 17 will be swung back to the position it is shown as occupying in Fig. 1. This procedure takes the stud or pin 23 from out of engagement with the cams 22 but the cover cannot be released until the studs 26 are out 85 of the offsets 27. To accomplish this it is necessary at this time to slightly lift the cover to cause the studs 26 to leave the offsets by for instance the elevation of the part 10 of the cover 9 to the dotted position X in 90 Fig. 1. This lifting of the cover section in this manner will cause the studs 26 to relatively pass out of the offsets 27 and the actuator being in the "off" relation, the upper section 11 of the cover may be easily swung 95 up or to the dotted position Y in said Fig. 1. To close the cover the reverse action will be followed so as to obtain the relation shown for instance in Fig. 2. By lifting the forward section of the cover, access may 100 be readily had to the interior of the box for supplying it for instance with a fuse or performing some other desired action. It will of course be understood that before the upper or larger section 11 of the cover can 105 be swung up, it will be necessary to move the catch 14 to releasing position.

Access is desirably had to the lower portion of the box by bodily raising the cover 9 and I will explain the construction shown 110 by which this is made possible. The cover section 10 is shown as having fastened to the under lower side thereof the shanks of fingers as 28. These fingers generally consist of some flexible or bendable metal and they are associated with the box body in some proper manner as by projecting them through slots 29 in the bottom or lower end wall of the body near the upper edge thereof and when they are all the way through the slots, bending their free portions so that they can abut or nearly abut against the lower edge of the cover. Before the lower section 10 of the cover can be opened therefore, it is necessary to remove the holding hooks 30 thereof. 115 Either before or after this the actuator 17 will be moved to open circuited relation and the studs 26 relatively carried out of the offsets 27 in the manner hereinbefore described. This will permit the lifting of the 120 125 130

cover 9 and if the hooks 30 have been bent out will permit the fingers 28 to be taken out of their slots 29 and the resultant elevation of the section 10 as shown for example by dotted lines Z in Fig. 3.

What I claim is:

1. An electric-appliance-receiving box comprising a body and a cover, an actuator for switch mechanism in the box, a plate 10 rigid with the cover and having a slot furnished with a lateral offset, a stud on the body of the box, and means on the cover and engageable by the actuator for maintaining the stud in the offset when the actuator is in the "on" relation and for permitting the stud to leave the offset when the actuator is in the "off" relation.

2. An electric-appliance-receiving box comprising a body and a cover, an actuator for switch mechanism in the box, a part 20 rigid with the cover and having an arcuate slot furnished with a lateral offset, a stud on the body of the box to enter the slot and its offset, and cam means on the cover engageable by means on the actuator for main-

taining the stud in the offset when the actuator is in the "on" relation, and for permitting the stud to leave the offset when the actuator is approximately in the "off" relation.

3. An electric-appliance-receiving box comprising a body and a cover, an actuator for switch mechanism in the box, extending through the cover, a plate rigid with the cover extending into the body of the box 35 when the cover is on, the plate having a slot furnished with a lateral offset, a stud on the body of the box to project into the slot, cam means on the cover, and a pin on the actuator to engage the cam means to 40 maintain the stud in the offset when the actuator is in the "on" relation and to permit it to leave the offset when the actuator is in the "off" relation.

In testimony whereof I affix my signature. 45

MONROE GUETT.

In presence of—

A. J. BENNETT,
CARL F. HAMMON.
